ELECTRO PLUMB BOB

Edward C. Mitchell, San Diego, Calif.

Application June 24, 1950, Serial No. 170,126

5 Claims. (Cl. 33—216)

1

My invention relates to electro plumb-bobs, and its objects are, to provide a line plumbing device for readily determining, locating, illuminating and allowing the marking of the exact spot to be plumbed, particularly as used by mechanics for the accurate work required in the assembly of parts of airplanes or other sizable mechanical constructions, or as used by carpenters and others in the building trades; to secure such illumination and to determine such location through a plumb-bob provided with a centrally apertured tip or plummet adapted accurately to direct a beam of light upon the point so to be determined; to employ a novel arrangement of a magnifying lens bulb, reflector, and dry batteries installed within the barrel of the bob in producing said beam of light and in effecting said illumination; to allow the ready installation and removal of said bulb, reflector and batteries within and from the said bob; to provide an improved switch for manually turning on and off the light of the bob; to render the parts accessible for inspection, adjustment, removal, replacement and repair; and in general to provide an electric plumb-bob which is simple and economical of construction, saving of labor, efficient in action and of prolonged life and durability. These and other objects will appear from the drawing and as hereinafter set forth.

My invention generally consists in constructing a plumb-bob in the form of a cylindrical casing, the lower end or tip of which closed except for a centrally located narrow straight passageway of uniform diameter extending downwardly therefrom; and within the main body of which casing is formed an elongated chamber, whose walls are shaped to locate and seat an electric lamp positioned to cast concentrated rays of light downwardly through and out of said passageway, a contact reflector washer cooperating with said bulb in the intensified gathering and casting of said rays, and a dry cell battery electrically connected with said bulb for energizing the same; the wall of said chamber adjacent to the top of said plumb-bob being in threaded engagement with a thumbscrew plug serving as a switch for turning on or off the light of said bulb through suitable electrical connections made therewith and therefor.

My invention further consists in other novel features of construction, and combinations and arrangements of parts illustrated in the drawing, and hereinafter more specifically described and claimed.

Attention is hereby directed to the accompanying drawing, illustrating a preferred form of my invention, in which similar numerals of designation refer to similar parts throughout the several views, and in which—

Figure 1 is an upright side elevational view

of a plumb-bob embodying said form of my invention, and

Fig. 2 is a longitudinal section thereof, turned on its side and showing the magnifying lens bulb, contact reflector washer, battery, and thumbscrew cap and associated parts in their respective relative positions inside of the plumb-bob.

Referring to the drawing, the plumb-bob there shown generally comprises, the upright barrel or elongated rounded casing 3, having integral therewith the perforated conical lower end 4; and the manually adjustable closure plug cap 5 threaded to engage with the upper end of said barrel, both said casing and cap being of electric conducting material. Within the bore of said barrel and extending nearly the length thereof is the chamber 7; and within said chamber and in sliding engagement with the wall thereof is the dry battery 8 of conventional form and whose ends are supplied with the usual electric contacts. At the lower end of said chamber 7, the wall thereof is constricted to form the tapered shoulder 9, the rounded vestibule 10, and the narrow straight aperture 11 of uniform diameter or cross section throughout opening downwardly therefrom. All of these inside parts and openings are axially aligned with the barrel of the plumb-bob.

Seated upon the shoulder 9, with its bulb 12 downwardly extending to enter and to effect close engagement with the wall of the vestibule 10, is the electric lamp 13, the threaded shank 14 of which extends upwardly, and the electric contact 15 of which is centrally positioned to engage with the lower contact 16 of the battery 8. Preferably the lower end of said bulb 12 is provided with the magnifying lens 17, and secured immediately above said bulb to the body of the lamp 13 and resting upon the shoulder 9, is the washer 18 of electric conducting material, the lower face of which is silvered or processed to reflect downwardly such rays of the lamp 13 as are projected upwardly therefrom, and the rim of which is in sliding engagement with the wall of the chamber 7, and adapted to make electric contact therewith.

As illustrated in the drawing, the magnifying lens bulb 13, reflector washer, the parts for seating said lamp, and the small aperture aforesaid are centered and co-ordinated so as to gather and concentrate the rays of light coming from the bulb so as to cast downwardly a beam of light through said aperture and to produce upon the surface of the object beneath a spot of light of minute size, serving as a convenient means of locating the exact plumbing point desired to be determined through the use of the bob.

As shown, the plug cap 5 is provided with the central aperture 19 extending therethrough, which aperture communicates with the socket 20

formed in the bottom portion of such plug, and within which socket is lodged the knotted end of the plumb-line 24 driven outwardly through the aperture 19, which line serves to suspend therefrom the plumb-bob as a whole. For the purpose of engaging the upper electric contact of the battery 8, I preferably taper the bottom portion of the plug 5 outside of the wall of said socket so as to form a nose, the end of which being forced downwardly upon rotation of the plug will effect said engagement. In order, however, that the said plug and battery may normally be out of engagement, when the plumb-bob is not in use, I prefer to interpose therebetween the washer 22 of sponge rubber or rubberlike material serving as insulation between the two; but the opening of such washer being sufficiently wide as to permit said nose to be impressed and thrust therethrough and to engage the said upper contact of the battery and thereby to turn on the light and to act as a switch in the way well understood in the art.

In order that the plumb-bob above described may be effective for all the purposes above set forth, all parts of the bob and all the openings therein must be in accurate axial alignment with the axis thereof, and balanced distribution of the weight of such parts about a common center must be accomplished, so that the bob may be undeviatingly accurately suspended above the spot to be plumbed. Also it is important that the passageway of the narrow aperture 17 should be uniform in cross section throughout, and preferably circular in form, in order that the concentrated rays projected downwardly from the bulb 12 and intensified by the magnifying lens 17 thereof, and reflective surface of the washer 18, may produce effectively the small distinctive light spot which it is the main object of the invention to secure.

To operate the device, for example, the light is first turned on through manipulation by the workman of the switch plug 5, and the bob is thereupon suspended from a bulkhead, a stringer, or other object directly above the point whose plumbed location it is desired to determine, whereupon the said point being so located by the beam of light being thrown thereon, such location is carefully marked and the work predicated thereon allowed to proceed accordingly with great saving of labor, time and computation.

My invention may be embodied in other specific forms without departing from the spirit or essential characteristics thereof. The present embodiment, as above set forth is therefore to be considered in all respects as illustrative and not restrictive, the scope of my invention being indicated by the appended claims rather than by the foregoing description, and all changes which may come within the meaning and range of equivalency of the claims are therefore intended to be embraced therein.

What I desire to secure by Letters Patent is:

1. An electric plumb-bob, comprising an upright symmetrically formed curvilinear casing of electric conducting material with tip closed at the bottom except for a narrow aperture of uniform diameter extending downwardly from the hollow of said casing; an electric lamp seated within said casing and positioned to cast downwardly a beam of light through said aperture to form a pin point illuminated spot upon the surface below; a dry cell electric battery located within said casing and adapted to be electrically connected to energize said lamp; and a cap plug

of electric conducting material threaded to engage with the top of said casing and positioned resiliently to make contact with the upper contact of said battery and to serve as a switch for opening and closing the circuit thereof through said lamp; the said cap having a central aperture extending therethrough and merging into a socket adapted to receive the knotted end of the plumb line, and to lodge the same therein.

2. An electric plumb-bob, comprising an upright symmetrically formed casing of electric conducting material closed at the bottom except for a narrow aperture extending downwardly from the hollow of said casing; an electric lamp seated within said casing and positioned to cast downwardly a beam of light through said aperture to form a pin point illuminated spot upon the surface below; a dry cell battery located within said casing and adapted to be electrically connected to energize said lamp; a plug cap of electric conducting material tapered at the bottom to form a downwardly projecting nose and threaded to engage with the inside of the top of said casing; a washer of insulating rubber-like material having its opening smaller than the end of said nose and normally interposed within said casing between the upper contact of the battery and said projecting nose, and allowing the end of such nose to be extruded through the opening in said washer and to engage said contact upon the turning down of said cap on said washer and compression thereof.

3. The subject matter of claim 2, the cap therein referred to having a central aperture extending therethrough and merging into a socket adapted to receive the knotted end of the plumb line and to lodge the same therein.

4. The subject matter of claim 2, including a disc light reflector of electric conducting material located within the casing above the lamp so as to reflect downwardly the rays of light coming upwardly therefrom and serving electrically as a contact to connect said lamp with said casing.

5. In an electric switch, the combination of a cylindrical casing having an electric contact therein, a plug cap of electric conducting material tapered at the bottom to form a downwardly projecting nose and threaded to engage with the inside of one end of said casing, a washer of insulating rubber-like material having an opening smaller than the end of said nose and normally interposed within said casing between said contact and said projecting nose, and allowing the end of said nose to be extended through the opening in said washer and to engage said contact upon the turning down of said cap on said washer and compression thereof.

EDWARD C. MITCHELL.
